UNITED STATES PATENT OFFICE.

JOHN W. HOWELL, OF NEWARK, NEW JERSEY, ASSIGNOR TO GENERAL ELECTRIC COMPANY, A CORPORATION OF NEW YORK.

FILAMENT-SUPPORT.

1,017,546.

Specification of Letters Patent. Patented Feb. 13, 1912.

Application filed December 28, 1906. Serial No. 349,794.

To all whom it may concern:

Be it known that I, JOHN W. HOWELL, a citizen of the United States, residing at Newark, county of Essex, State of New Jersey, have invented certain new and useful Improvements in Filament-Supports, of which the following is a specification.

This invention relates to an improvement in incandescent lamps, and more particularly to an improved means for supporting the filament and for conducting current thereto.

My invention is applicable to lamps and other apparatus having filaments of tungsten, molybdenum, tantalum, and other refractory elements or compounds operative at high temperatures.

Tungsten lamp filaments can be satisfactorily connected with the leading-in wires of a lamp by fusing the end of the lead-wire to the end of the filament to make what may be termed a welded joint. Such a joint is entirely free from carbonaceous paste and does not give off any vaporizable foreign matter which might contaminate the filament during normal operation of the lamp.

My present invention comprises a holder and current conductor support also free from paste or vaporizable material and possesses several advantages over such a welded joint connection. A good electrical connection is secured between the leading-in wire and the filament without a fusing operation, and the various elements are so arranged that in case a filament becomes broken or worn out it may be replaced by a new filament introduced through a small hole at the top of the lamp. This renewal of the lamps may be carried out even with a relatively fine and fragile filament without any disturbance of the seals at the base of the lamp.

The details of my invention will be better understood by reference to the accompanying drawings forming a part of this specification.

Figure 1 is a perspective view showing my invention applied to a single filament lamp; and Fig. 2 is a detail of the filament holder.

The lamp shown in Fig. 1 comprises the usual glass envelop 1, and stem 2, and is provided with a glass pedestal 3 supported by the stem and carrying at its top a copper standard 4 sealed in the end of the glass pedestal 3. The copper standard carries at

its top a tantalum wire spring 5 of helical form to serve as a support and anchoring means for the lamp filament 6. This tantalum coil is preferably clamped or pinched in the end of the copper standard and is so arranged as to be subjected to transverse flexure when the filament is in place. The lower ends of the filament are clamped in the conducting supports 7 shown in detail in Fig. 2. Each support consists of a flat strip 8 of copper or other suitable metal folded back on itself to form an eye or bend through which the end of the filament 6 passes with a loose fit. This copper strip may be welded or otherwise connected with the usual platinum leading-in conductor 9. About the folded strip is arranged a coiled spring 10 of tantalum held in place at one end by a stop 11 and at the other end pressed against the filament to hold it tightly against the flat copper strip and insure good electrical contact between the filament and the other elements.

Even though the filament may be made of tungsten and operated at an exceedingly high temperature, the tantalum spring 10 does not appear to combine chemically with the filament and does not in any way change the refractory nature thereof.

In case a filament becomes damaged during transportation or during normal use of the lamp, the lamp bulb 1 may be opened at the top according to methods now in common practice with respect to carbon filament lamps, and a new filament may be introduced through this small opening and may be slipped into place in the holder. No paste is required and the operation is so simple that it can readily be carried out on a commercial basis. The spring 5 normally holds the filament under tension and tends to draw the filament from the bent support 8, but the tantalum spring 10 yieldingly holds the filament in contact with the bend or eye and thus resists the disengaging action of spring 5. If the tension on the filament becomes excessive, as for instance, by carelessness of the operator in mounting the filament, the filament, being held in position only by frictional engagement due to the lateral pressure of the spring 10 thereon, will slip through the holder 8 so as to relieve the excess tension.

Although I have shown a single filament

lamp, my invention is applicable to lamps having more than one filament or loop, as will be readily understood.

What I claim as new and desire to secure 5 by Letters Patent of the United States, is:

1. The combination of a filament, supporting means therefor through which the filament passes, and a refractory metal spring yieldingly pressing the filament laterally against said supporting means and holding the filament in position by frictional engagement.

2. In combination with a filament, a conductive strip embracing said filament, and a tantalum spring yieldingly pressing the filament laterally against said strip and holding the filament in position by frictional engagement.

3. The combination of a filament, a conductive support engaging therewith, and a tantalum wire spring yieldingly pressing the filament laterally against said support and holding the filament in position by frictional engagement.

4. The combination of a leading-in conductor, a strip connected therewith and folded into a bend, a filament passing through said bend, and a helical spring surrounding said strip and holding said filament in place.

5. The combination with a filament, of supporting means removably connected therewith, and a refractory spring contacting with said filament and holding it against said supporting means.

6. The combination with a filament, of supporting means detachably connected therewith, and a tantalum wire pressing against said filament to insure electrical connection between said filament and said supporting means.

7. The combination of a fragile metal filament, means for holding said filament under

tension during normal use, and current-supply means detachably clamped to said filament and by frictional engagement with said filament resisting the normal tension on said filament of said holding means. 45

8. The combination of a fragile metal filament, means for normally holding said filament under tension, current-supply means, and a spring normally insuring contact between said filament and said current-supply means and by the friction of said contact resisting the normal tension on said filament of said holding means. 50

9. The combination of a metal filament, a supporting member through which the filament passes, a spring tending to draw said filament from said member and a second 60 spring holding said filament in said member and by frictional engagement preventing the withdrawal of the filament by the normal tension of said spring.

10. The combination of a leading-in conductor, a strip connected therewith and folded into a bend, one end of said strip being bent outward to form an abutment, a filament passing through said bend, and a helical spring surrounding said strip and 70 compressed between said filament and abutment so as to retain the filament in place. 65

11. The combination of a fragile filament, current supply means with which said filament is in contact, means for holding said 75 filament under tension during normal use which tends to disengage said filament from said current supply means, and resilient means for resisting the disengaging action of said holding means. 80

In witness whereof, I have hereunto set my hand this 24th day of December, 1906.

JOHN W. HOWELL.
